UNITED STATES PATENT OFFICE.

FRANK C. HOBBS, OF MUSKEGON, MICHIGAN, ASSIGNOR TO THE BRUNSWICK-BALKE-COLLENDER COMPANY, OF CHICAGO, ILLINOIS, A CORPORATION OF DELAWARE.

BOWLING-ALLEY PIN-SETTER.

1,162,923.

Specification of Letters Patent.

Patented Dec. 7, 1915.

Application filed August 27, 1915. Serial No. 47,571.

To all whom it may concern:

Be it known that I, FRANK C. HOBBS, a citizen of the United States, residing at Muskegon, in the county of Muskegon and State of Michigan, have invented certain new and useful Improvements in Bowling-Alley Pin-Setters, of which the following is a specification.

This invention relates to bowling-alley pin-setters of that type which are arranged to swing in an arc above the pin end of the alley bed and are provided with a shifting frame to upright the pins from a substantially horizontal position in the machine and assist in setting them properly on the bed.

The object of the invention is to provide a machine of simple and inexpensive construction, comprising but few movable parts and adapted for rapidly and accurately setting the pins upon the spots on the alley bed.

Further objects of the invention are to provide improved means for actuating the shifting frame by contact with the alley bed for positioning the pins upon the spots on the alley bed, and for counter-balancing the machine.

Referring to the drawings, Figure 1 is a plan view of the machine shown in the position indicated in broken lines in Fig. 2, 30 the cushion on the alley being omitted. Fig. 2 is a sectional side elevation showing the machine in elevated position in full lines, with the pins indicated in broken lines, and in lowered position in broken lines. Fig. 3 is a detail enlarged sectional view showing the front portion of the machine in elevated position. Fig. 4 is a similar view in lowered position. Fig. 5 is a detail enlarged sectional view of a portion of the main frame with the shifting frame removed. Fig. 6 is a detail view of the front end of the machine showing a pin in set position. Fig. 7 is an elevation of the counter-balance devices located in the pit behind the cushion, the kickbacks being shown in section. Fig. 8 is a detail sectional view of a portion of the machine at the rear thereof and Fig. 9 is a detail view showing a connection between the frame and the arms.

50 Referring to the drawings, the invention comprises a main frame 10 which is gen-

erally triangular in shape and has a plurality of substantially parallel longitudinal bars 11 and intermediate braces 12. Angular arms 13 are pivotally mounted at 14 to side plates 15 located behind the cushion 16 on the kickbacks 17 and these arms extend forward close to and alongside the kickbacks and are adjustably connected with brackets 18 mounted on the rear corners of the main frame (Figs. 1, 2). Levers 19 are pivotally mounted on the cross bar 20, supported in the plates 15, and these levers have rearward extensions 21 which are connected to and adapted to operate the levers 22 pivoted at 23 in the plates 15 and carrying the weights 24 (Fig. 7). It will be noted that the weight levers extend transversely across the pit of the alley, behind the cushion, and that the plates 15 and the pivot ends of the arms 14 and levers 19 are also located in a compact manner behind the cushion. This is a distinct advantage in machines of this type because it confines these parts to a very small space where they will be entirely out of the way and will not interfere with the game, or the operation of the machine, or with the pin-boy.

The forward ends of the levers 19 are provided with rollers 19' which operate against the plates 25 on the arms 13. These plates are located at the bend in the arms and they are provided with two adjacent sockets 25', 25" in which the rollers 19' operate. When the machine is in elevated position the rollers 19 are seated in the sockets 25", as shown in full lines in Fig. 2; when the machine is in lowered or setting position the rollers will be seated in the sockets 25', as shown in broken lines in Fig. 2. While the machine is traveling between the elevated and lowered positions the rollers will ride over that part of the plates 25 which forms a partition between the sockets 25' and 25", and as some positive force is required to accomplish this, it will be apparent that the chances of accidental movement of the machine are thereby almost entirely eliminated. Furthermore, these sockets, in conjunction with the rollers 19' and levers 19, act as centering or positioning means for the machine, the socket 25" serving to posi-

tion the machine in elevated position and the socket 25' serving to position the machine in lowered or setting position, as shown in Fig. 2. This engagement of the rollers 5 in the sockets also steadies the machine and eliminates any tendency of the machine to jump or quiver in its elevated or lowered positions.

The frame is arranged to swing above the 10 pin-end of the alley bed and is counterbalanced by the weights 24 in the manner common to this type of pin-setters, but the construction and arrangement of parts hereinbefore described is of importance because 15 they are almost entirely concealed from view and are arranged out of the way and where they will not be struck by the pins and balls. This is especially important with regard to the weights which are sufficient to counter-balance the machine when 20 loaded and which are concealed behind the cushions.

The frame is provided with a plurality of 25 pockets 26, one for each pin, and each pocket has a head guide 27 and body guides 28.

A shifting frame 29 of suitable construction 30 is located above the main frame and pivotally connected therewith by links 30 and is provided with a cross bar 31 for each 35 pin pocket. The shifting frame is operated when the machine reaches lowered position and at the proper time to deposit the pins, as hereinafter described, upon the spots on the alley bed. This movement is effected 40 by an operating foot, in the form of a roller 32, carried by a substantially vertical lever 33 pivotally connected at 34 to the shifting frame and by a substantially horizontal lever 35 pivotally connected at 36 to a bracket 40 37 on the main frame (Figs. 3, 4), the construction being such that when the roller engages the alley bed the lever 33 will lift the shifting frame which will swing forward under the influence of links 30. As the 45 machine is raised to elevated position the shifting frame will return by gravity to its normal or folded position at rest upon the main frame (Fig. 3). Springs 38 are arranged at suitable locations on the main frame to receive the shifting frame when it 50 returns to normal position and relieve the machine from shock or jar.

A handle 39 is provided at the rear of the 55 main frame to facilitate the movement of the machine by the pin-boy and one or more cushioned stops 40 are arranged on the main frame to engage the alley and limit the downward movement of the machine.

In practice the machine is loaded in elevated 60 position, the pins being placed in reclining position in the pockets, as shown in Figs. 2 and 3. In this position the pin is supported on the body guides 28 of the main frame and the cross bar 31 of the

shifting frame with the upper edge of its 65 base engaging the front portion of the pocket, as shown in Fig. 3. As the machine is brought to rest upon the alley bed the shifting frame is swung forward whereby the cross bar 31 uprights the pin in the 70 pocket and the pin falls down upon the alley bed. The shifting frame continues its forward swinging movement until the cross bar 31, engaging the neck of the pin, clamps the pin against the head guide and the lower 75 front portion of the pocket, whereby the pin is centered in position on the spot of the alley bed (Fig. 4). The guides 28 serve to assist in supporting the pin in reclining position and also to guide the pin while it is 80 being uprighted in the pocket by the cross bar of the shifting frame, but these guides are not necessary in positioning the pin upon the spot because the cross bar 31 of the shifting frame clamps the pin between itself 85 and the head guide 27 and pocket 26. As the machine is lifted the shifting frame swings back to normal position, carrying the clamping cross bar away from the pin 90 and the head guide and pocket clear the pin 95 so that it will not be disturbed in the return movement of the machine.

My present machine is preferably made of skeleton form and almost entirely of metal 95 of commercial sections, the parts being riveted or bolted together to produce a strong and substantial but comparatively cheap machine which will not easily get out of order and which can be operated quickly to accurately position the pins on the spots of 100 the alley bed.

I claim:

1. In a pin-setter for bowling-alleys, the combination of a pivoted frame, and a counter-balance lever connected with the frame 105 and operating in a plane at an angle to the direction of the plane of movement of the frame.

2. In a pin-setter for bowling-alleys, the combination of a pivoted frame, and a pair 110 of counter-balance levers connected with the frame and each operating in a plane at an angle to the direction of the plane of movement of the frame.

3. In a pin-setter for bowling-alleys, the 115 combination of a pivoted frame, and a pair of oppositely disposed counter-balance levers connected with the frame and each operating in a plane at an angle to the direction of the plane of movement of the frame. 120

4. In a pin-setter for bowling-alleys, the combination of a frame pivoted to operate above the pin end of the alley bed, and a counter-balance lever connected with the frame and arranged transversely of the alley to operate in a plane at an angle to the direction of the plane of movement of the frame. 125

5. The combination of a bowling-alley comprising a bed and a cushion, a pin-setter pivoted to swing over the pin end of the bed, counter-balancing means located behind the 5 cushion and connections between said counter-balancing means and pin setter, said counter-balancing means and connections being arranged to remain always below the plane of the upper range of movement of 10 said pin setter.

6. The combination of a bowling-alley comprising a bed and a cushion, a pin-setter pivoted to swing over the pin end of the bed, and counter-balancing means comprising 15 a weighted lever arranged behind the cushion transversely of the alley to operate at an angle to the direction of movement of the frame.

7. The combination of a bowling-alley 20 comprising a bed and a cushion, a pin-setter pivoted to swing over the pin end of the bed, and counter-balancing means comprising a pair of oppositely disposed weighted levers arranged behind the cushion transversely 25 of the alley to operate at an angle to the direction of movement of the frame.

8. The combination of a bowling-alley comprising a bed, a cushion and kickbacks, a pin-setter arranged to swing over the pin 30 end of the alley bed, arms connected to said pin-setter and pivotally mounted on the kickbacks behind the cushion, and means for counter-balancing the pin-setter.

9. In a pin-setter for bowling alleys, the 35 combination of a frame arranged to swing over the pin end of the alley bed, rearwardly extending arms connected to said frame and pivotally mounted at their rear ends, levers arranged to engage said arms to lift the pin-setter and control its downward movement, and pivotally mounted counter balance means for said pin-setter connected with 40 said levers.

10. In a pin-setter for bowling alleys, the 45 combination of a frame arranged to swing over the pin end of the alley bed, rearwardly extending arms connected to said frame and pivotally mounted at their rear ends, levers pivotally mounted at their lower ends and 50 arranged at their upper ends to engage said arms to lift the pin-setter and control its downward movement, and counter-balance means for said pin-setter connected with said levers.

55 11. In a pin-setter for bowling alleys, the combination of a frame arranged to swing over the pin end of the alley bed, rearwardly extending angular arms connected to said frame and pivotally mounted at their 60 rear ends, pivoted levers having their upper ends arranged to engage the arms at the bend therein, and counter-balance means for said pin-setter connected with said levers.

12. In a pin-setter for bowling alleys, the 65 combination of a frame arranged to swing over the pin end of the alley bed, rearwardly extending arms connected to said frame and pivotally mounted at their rear ends and each provided with a socket, pivoted levers having their free ends arranged to engage said socket and adapted to be operated to lift the pin-setter and control its downward movement, and counter-balance means for said pin-setter connected to said 70 levers.

13. In a pin-setter for bowling alleys, the combination of a frame arranged to swing over the pin end of the alley bed, rearwardly extending arms connected to said 80 frame and pivotally mounted at their rear ends and each provided with a pair of sockets, pivoted levers having their free ends arranged to engage said sockets and adapted to be operated to lift the pin-setter and 85 control its downward movement, and counter-balance means for the pin-setter connected to said levers.

14. In a pin-setter for bowling alleys, the combination of a frame arranged to swing 90 over the pin end of the alley bed, rearwardly extending angular arms connected to said frame and pivotally mounted at their rear ends and each provided with a pair of sockets at the bend therein, pivoted levers having their free ends arranged to engage said 95 sockets and adapted to be operated to lift the pin-setter and control its downward movement, and counter-balance means for the pin-setter connected to said levers. 100

15. In a pin-setter for bowling alleys, the combination of a frame arranged to swing over the pin end of the alley bed, rearwardly extending arms connected to said 105 frame and pivotally mounted at their rear ends, levers coöperating with said arms to lift the pin-setter and control its downward movement, means for steadyng the operation of said pin-setter, and counter-balance means for the pin-setter connected to said 110 levers.

16. In a pin-setter for bowling alleys, the combination of a pivoted main frame arranged to operate above the pin end of the 115 alley bed, a shifting frame pivotally mounted on the main frame, a roller arranged to engage the alley bed, and levers connecting said roller with the main frame and shifting frame, respectively.

17. In a pin-setter for bowling alleys, the 120 combination of a main frame arranged to swing over the pin end of the alley bed, a shifting frame pivotally mounted on the main frame, a roller arranged to engage the alley bed, a substantially vertically arranged 125 lever pivotally connected with said roller and with the shifting frame, and a substantially horizontally arranged lever pivotally

connected with said roller and with said main frame.

18. In a pin-setter for bowling alleys, the combination of a frame, a plurality of pin pockets arranged in the frame and comprising a pair of complementary body guides and an oppositely disposed head guide, a

shifting frame on the main frame, and a cross bar on the shifting frame opposite each pocket to engage the neck of the pin.

FRANK C. HOBBS.
